UNITED STATES PATENT OFFICE.

THOMAS MILES BANNISTER, OF LONE PINE, CALIFORNIA.

BRICK-CUTTING MACHINE.

SPECIFICATION forming part of Letters Patent No. 295,097, dated March 11, 1884.

Application filed December 28, 1882. (No model.)

To all whom it may concern:

Be it known that I, THOMAS MILES BANNISTER, of Lone Pine, in the county of Inyo and State of California, have invented a new and Improved Brick - Cutting Machine, of which the following is a full, clear, and exact description.

The object of the invention is to improve brick - cutting machines, as hereinafter described, and pointed out in the claims.

Reference is to be had to the accompanying drawings, forming part of this specification, in which similar letters of reference indicate corresponding parts in all the figures.

15 Figure 1 is a longitudinal sectional elevation of my improved brick-cutting machine. Fig. 2 is a transverse sectional elevation. Fig. 3 is a portion of one of the reel-heads, showing the contrivance of the reel wire-supporting arms; and Fig. 4 is a detail of the guiding or regulating contrivances of the cutting-wires, the same being in plan view.

The pressed clay is to be delivered from the pressing-machine, by any suitable means, in 25 cakes on trucks *a*, which are to be caused to move successively along ways *b* under a reel, between whose heads *c* cutting-wires *d* are stretched at suitable distances apart, to cut the said clay cakes transversely by the rotation of the reel as the car moves along, the 30 said wires being guided or controlled by the vertical traveling guides *e*, so as to be made to enter and retire from the clay in vertical lines, to make square corners on the bricks, 35 and the arms *f*, by which the said wires are supported, being capable of springing between the pins *g* and *h* in the reel-heads, to allow such operation of said wires. When the clay is delivered from the pressing-machine onto 40 the trucks, it is to be divided longitudinally in any approved way into cakes equal in width to the required length of the bricks to be cut, as shown at *j*, Fig. 2. The cutting-wires are then placed suitably distant from each other, 45 to cut the bricks edgewise, as shown at *j'*, Fig. 1; but it is to be understood of course that the cakes may be delivered in suitable breadth for the width of the bricks to be cut at the ends of the bricks by the wires, if desired. The 50 reel-arms *f* are required to spring more, or,

rather, to have more freedom to spring when the cutting-wires enter the clay and perform their work than when withdrawing from the same. Consequently, I locate the pins *h*, over which the arms spring when the clay is being 55 cut, near the inner ends of the arms, and place pins *g* nearer the outer ends, thus allowing the arms greater range in the one case than in the other. The said arms are arranged at each side between two disks forming each head of 60 the reel, to which they are connected by pins *i*, extending from one disk to another through eyes of the arms. The pins *g* and *h* are similarly fixed in the disks, and the disks are connected together by larger pins, rivets, or bolts 65 *k*, besides being mounted on a shaft, *l*, which is suitably mounted in bearings in the side frames or housings, *m*. The cutting-wires *d* are stretched from the arms of the respective 70 heads of the reel by means of adjusting thumbscrews *n*, to which they are connected so as to be tightened by the turning of the thumbscrews in the arms and twisting the wires, the said screws screwing forward and backward in the arms; but the wires may be connected to the screws so as not to be twisted by turning the screws. The guides *e* are carried 75 on endless chains *o*, working on rollers *p*, suitably arranged in the machine. In practice the reel may also be contrived to carry printing devices to impress the upper surface of 80 the bricks *q*, and lightly print numbers or characters thereon.

The machine will connect at each end, respectively, with tracks from the press, and extending to the drying - yard, kiln, or other place, as desired, for simple and economical transference of the clay to the machine to be cut, and the cut bricks, therefrom to the place of delivery.

Having thus described my invention, what I claim as new, and desire to secure by Letters Patent, is—

1. In a brick-machine, the combination, with the rotary cutters *d*, of an endless belt, *o*, provided with guides *e*, arranged in pairs, with an opening between them, substantially as herein shown and described, whereby a square cut will be insured, as set forth.

2. In a brick-machine, the combination of 100

the heads *c c*, and the arms *f*, carrying cutters *d*, with the truck *a*, and the endless belt *o*, provided with the guides *e*, substantially as shown and described.

5. 3. The wire cutters *d* of a brick-cutting reel, mounted on spring-arms *f*, arranged between supporting-pins *g h*, and connected to pins *i* in the reel-heads, substantially as described.

4. In a reel of clay-cutting wires, *d*, mounted 10 on spring-arms *f*, the arrangement of the supporting-pins over which the arms spring, whereby said arms may have greater range for springing when cutting the clay than when returning therefrom, substantially as described.

5. In a reel of clay-cutting wires, *d*, mounted 15 on spring-arms *f*, which are supported between pins *g* and *h* in the reel-heads, the said supporting-pins located in the heads to allow the said arms greater range of spring in one direction than the other, substantially as de- 20 scribed.

THOMAS MILES BANNISTER.
